UNITED STATES PATENT OFFICE.

ERNEST KREHER, OF TAMPA, FLORIDA.

SIGN-APPLYING TOOL.

1,222,418.

Specification of Letters Patent. Patented Apr. 10, 1917.

Application filed January 6, 1916. Serial No. 70,638.

To all whom it may concern:

Be it known that I, ERNEST KREHER, a citizen of the United States, residing at Tampa, in the county of Hillsborough and State of Florida, have invented certain new and useful Improvements in Sign-Applying Tools, of which the following is a specification.

This invention has reference to an improved device for applying signs, or the like, high up on supports, such as telegraph poles, trees, or the like, and has for an object to provide a simple, compact, and easily manipulated device for quickly and accurately applying signs, particularly of the type disclosed in my co-pending application, filed of even date herewith, to the support by a person standing on the ground.

The sign applying tool comprises means for holding a sign against a support in line with the tool while a striking device movable longitudinally of the tool is operated to deliver blows against the sign to secure it to the support in an initial angular position with respect thereto. The tool is also provided with means for then engaging the sign to bend the latter from the initial angle of application into the desired display angle with respect to the support. Various other objects and advantages of this invention, as well as the above, will be more clearly brought out in the following description of the present preferred embodiment of this invention, the same being disclosed in the accompanying drawings, wherein:

Figure 1 is a side elevation of the improved tool as applied to a sign to hold the latter in position for hammering or driving the sign into a support.

Fig. 2 is a similar view, disclosing the sign secured to the support, and the tool adjusted upon the sign for bending the latter upwardly into the desired permanent position, the dotted lines disclosing the sign in the permanent position.

Fig. 3 is a fragmentary sectional view of the sign engaging end of the tool applied to the sign to hold it.

Fig. 4 is a similar view, disclosing the application of the tool to the sign for adjusting the latter.

Fig. 5 is an edge view of the tool collapsed.

Fig. 6 is a side elevation of the tool partly in section, and showing the parts slightly

opened, and showing in dotted lines the tool fully collapsed and secured from accidentally opening.

Referring to the drawings there is shown a tubular pole 10 of sufficient length to enable an operator standing on the ground to place a sign high up on a pole or tree. The tube 10 is open throughout its entire length and contains a hammer rod 11 of a length to extend substantially the full length of the tube 10 and project from one end thereof where the rod is formed into a handle 12. The tube has near the end from which the handle end of the rod projects a socket opening 13 formed by notching the opposite edges of a longitudinal entering slit 14. The tube where slit is sufficiently elastic so that the edges of the slit will spread slightly to admit a pin 15 on the hammer rod 11 to enter the slit and temporarily lock in the socket notches 13.

The end of the tube 10 remote from the handle 12 is open to receive a portion, such as an extension 17, of the sign, for a sufficient distance to support the sign in longitudinal alinement with the tube and against a tree or other support 18. At the end designed to receive the extension 17 the tube 10 is provided with a lip 19 in line with one side of the tube. The lip conforms to the contour of the tube and extends circumferentially for not more than about one-half of the distance around the tube. That portion of the end of the tube at the base of the lip 19 forms an abrupt shoulder 20 designed to engage one side of the extension 17 when the other end of the tube 10 is swung downwardly toward a vertical position as shown in Figs. 2 and 4, so that the extension 17 may be forced upwardly to bend the sign to a display position after being secured to the tree 18 or other support in an inclined position.

The sign comprises a body 21 of flat or other suitable form secured by clips 22, upon a rod or arm 23, which latter is pointed at one end to provide a piercing point or prong 24 joined to the rod 23 by a bendable connection or joint 25. The other end of the rod 23 projects beyond the body 21 for a short distance, and this projection constitutes the extension 17 before referred to.

The sign applying tool may be used with signs of various constructions or may be used for other purposes than securing signs to supports, but for simplicity of descrip-

tion the operation will be set forth in connection with the specific form of sign shown and described.

An operator standing on the ground 5 places the extension 17 of the sign in the outer end of the tube 10, thus supporting the sign in line with the tube, and then the operator raises the tube with the sign sufficiently to position the piercing point 24 of 10 the sign against the support 18 at a high point thereon desired, and this high point is generally above any signs 26 which may have been previously applied to the support. Such signs are usually located close 15 to the ground. If found higher up the placing of them has probably necessitated the use of a ladder or some other similar device.

Because the tool and rod 23 are in alignment, the sign is held against the support 18 in an inclined position, as shown in Fig.

1. The operator reciprocates the rod 11 and therefore delivers a series of blows on the rod 23, thus driving the prong 24 into the support 18 with the rod 23 inclined. 20 25 The operator now draws the tube 10 from the extension 17 sufficiently to permit the lower end of the tube 10 to swing downwardly toward the support, so that the shoulder 20 will underride the free end portion of the extension 17, as shown in Figs. 2 and 4 of the drawings. During this operation the lip 19 serves as a guiding or holding device for retaining the extension 17 in engagement with the shoulder 20.

35 By lifting the tube, the rod or arm 23 of the sign is raised about the bendable portion 25 from the initial inclined position shown in Fig. 1 to the position shown in full lines in Fig. 2, and finally into the position shown in dotted lines in Fig. 2, this last-named position being the final or display position, customarily, with the rod 23 horizontal and the body of the sign pendent therefrom. These movements are permitted 40 45 by the bendable connection 25, so that the rod or arm 23 where carrying the body 21 of the sign is in no wise bent or distorted.

To collapse the tool for transportation or storage, the rod 11 is moved into the tube 50 55 10 until the handle 12 is close to the corresponding end of the tube 10 and the pin 15 enters the slit 14 and ultimately lodges in the socket notches 13, thus locking the two parts of the tool together against accidental displacement.

Since the tool includes but two parts, namely, the tube, which may be of ordinary construction, and the rod, which may also be of ordinary construction, the device can 60 65 be economically and easily manufactured, and will withstand wear and hard usage. Furthermore, the device requires no special skill in its operation. The device is also light in weight and occupies but relatively small space. It requires no adjustment and

is always in position for the next operation.

In order to facilitate grasping of the tool while the hammer rod 11 is reciprocated, there is provided a handle 27 formed on a sleeve 28 embracing the tube 10 and having an end 29 remote from the handle 27 traversed by a bolt 30 to which there is applied a nut 31 provided with a manipulating handle 32. The handle 27 is readily adjusted along the 70 75 tube 10 to different convenient positions where it may be clamped by a manipulation of the nut 31.

When the tool is collapsed for transportation or storage, the handle 27 is loosened from its operative position upon the tube and is moved so that the sleeve 28 is about the split end 14 of the tube where it is then clamped and rigidly holds the rod 11 in the tube.

80 The extension 17 of the sign has a pin 33 extending transversely through it, which pin may be a cotter pin, though not limited to such structure. This pin serves to hold the sign body 21 from slipping from the rod 23 and also serves as an abutment or stop for the lip end of the tool.

85 The length of the tool when extended in operative position will depend upon the particular use to which it is to be put, since it 90 95 may be employed for other purposes than lodging signs on supports. Moreover, for convenience of transportation the tool could readily be made of telescopic form, so as to admit of it being carried in a suit case.

100 The handle 27 projects from the sleeve 28 in a direction transversely of the tube 10 to an extent permitting ample hand room, and then the handle is continued lengthwise of the tube 10 to form a handhold with the 105 free end of the handle directed toward the tube 10. This provides a grasping member which is particularly effective for holding a long tube 10 near one end, with the other end carrying the sign with the piercing point high up on the support. It also permits the holding of the tube 10 with one hand, while the other hand engages the handle 12 with the rod 11 extending crosswise of the body of the operator, and consequently a long movement of the hammer rod 11 is permitted and powerful blows may be delivered upon the extension 17 to drive the piercing point 24 firmly into the support. This is especially of value where the 110 115 support is a tree or a pole which it is difficult to pierce and consequently heavy blows are needed to perform the driving of the point 24 so deeply into the tree or pole that the subsequent bending at the bending zone 120 125 25 may be accomplished without disturbing the initial position of the point 24 in the support.

What is claimed is:—

1. A tool for applying a sign provided 130

with a supporting rod having a penetrating prong at one end, comprising a tube having one end adapted to receive that end of the supporting rod remote from the prong to hold the remainder of the rod in projected relation to the tube with the prong high up against a support and with the tube and rod in substantial alinement, said tube having at the rod receiving end an elongated lip in alinement with the tube and extending circumferentially of the tube where joining the latter for a fractional portion of the circumference of the tube, and thereby providing an abrupt shoulder on and substantially radial of the rod receiving end of the tube and extending circumferentially of said tube and said lip and shoulder constituting an abutment and an engaging portion, respectively, for the supporting rod when the tube is at an angle to said rod, to bend the latter by an upward thrust of the tube subsequent to driving the penetrating prong into the support, and a hammer rod reciprocable in the tube for striking that end of the supporting rod lodged in the tube whereby to drive the piercing point into the support, and said hammer rod having the end remote from the striking end projecting beyond the corresponding end of the tube and there provided with a hand-hold.

2. A tool for applying a sign provided with a supporting rod having a penetrating prong at one end, comprising a tube having one end adapted to receive that end of the supporting rod remote from the prong to hold the sign high up against a support with the tube and supporting rod in substantial alinement, a handle on the end of the tube remote from that receiving the supporting rod, said handle being adjustable lengthwise of the tube, and a hammer rod reciprocable in the tube and projecting beyond the second-named end of the tube and there provided with a handle, the extent of adjustment of the handle lengthwise of the tube being sufficient to permit a wide separation of the hands of the operator in holding the tool and reciprocating the handle.

3. A tool for applying a sign provided with a supporting rod having a penetrating prong at one end thereof, comprising a tube having one end adapted to receive that end of the supporting rod remote from the prong with the tube and rod in substantial alinement, a reciprocable hammer rod in the tube projecting from the end of the latter remote from the first-named end and there provided with a handle, the tube and rod having coacting means for temporarily holding the rod at the point of full inward movement into the tube, and a handle on the tube having clamping means for binding the tube on to the rod to fixedly hold the hammer rod against withdrawal from the tube.

4. A tool for applying a sign provided with a supporting rod having a penetrating prong at one end, comprising a tube having one end adapted to receive that end of the supporting rod remote from the prong, a reciprocable hammer rod within the tube for delivering blows to the supporting rod, and a handle member on the tube having a gripping portion extending lengthwise of the tube. 75

5. A tool for applying a sign provided with a supporting rod having a penetrating prong at one end, comprising a tube having one end adapted to receive that end of the supporting rod remote from the prong, a reciprocable hammer rod within the tube for delivering blows to the supporting rod, and a handle member on the tube having a gripping portion extending lengthwise of the tube, said handle member being adjustable lengthwise of the tube and provided with means for clamping the handle member to the tube in different positions of adjustment. 80

6. A tool for applying a sign provided with a supporting rod having a penetrating prong at one end, comprising a tube having one end adapted to receive that end of the supporting rod remote from the prong, a reciprocable hammer rod within the tube for delivering blows to the supporting rod, and a handle member on the tube having a gripping portion extending lengthwise of the tube, said handle member being adjustable lengthwise of the tube and provided with means for clamping the handle member to the tube in different positions of adjustment, said clamping means having manipulating means for the actuation of the clamping means by hand without the aid of tools. 90 95

7. A tool for applying a sign provided with a supporting rod having a penetrating prong at one end and an extension at the other end, comprising a tube for engagement over the extension and having a split lower end with socket notches in the opposite edges of the split thereof, a hammer rod slidably in the tube for engagement against the extension to drive the prong into a support, a laterally extending pin on the hammer rod 110 for engagement in said socket notches to hold the rod collapsed, and a handle having a compressible sleeve adjustably mounted on the tube, for engagement over the split end thereof to bind the pin in the socket, and adapted for adjustment upwardly on the tube to position the handle for easy holding of the tool during use. 115 120

8. A sign applying tool comprising a tube for engagement at one end with a sign to hold it in position for application to a support, and a hammer rod mounted in the tube and projecting from the other end of the tube and there provided with a handle for the manual reciprocation of the rod in the 125 130

4

tube to deliver blows against the sign to secure the latter to the support, said tube being split at the second-named end and provided with sockets at the split portion, 5 and the hammer rod having a pin projecting therefrom for engagement in said sockets, whereby the hammer rod may be locked within the tube.

9. A sign applying tool comprising a tube 10 for engagement at one end with a sign to hold it in position for application to a support, and a hammer rod mounted in the tube and projecting from the other end of the tube and there provided with a handle for 15 the manual reciprocation of the rod in the tube to deliver blows against the sign to secure the latter to the support, said tube being split at the second-named end and pro-

vided with sockets at the split portion, and the hammer rod having a pin projecting 20 therefrom for engagement in said sockets, whereby the hammer rod may be locked within the tube, said tube being also provided with a handle having a clamp sleeve movable along the tube and adapted to embrace the split end of the tube and hold the latter with the pin lodged in the sockets for securely holding the hammer rod against withdrawal from the tube. 25

In testimony whereof I affix my signature 30 in presence of two witnesses.

ERNEST KREHER.
